SHOE SCRAPER AND CLEANER ASSEMBLY

Olive H. Cottingham, Lake, Mich.

Application March 19, 1940, Serial No. 324,872

2 Claims. (Cl. 15—112)

This invention appertains to new and useful improvements in means whereby shoes can be scraped clean without soiling the hands and is particularly adapted for use at farm homes.

The principal object of the present invention is to provide an assembly of the character stated which can be rigidly mounted for use and which will be effective in scraping boots and other foot-wear and adequately cleaning the same.

Another important object of the invention is to provide an assembly of the character stated which will be practical in use and which because of its sturdy construction will not become readily defective.

Still another important object of the invention is to provide an assembly of the character stated which will be of low cost to manufacture and which can be readily dumped when dirt is accumulated therein.

These and various other important objects and advantages of the invention will become apparent to the reader of the following specification.

In the drawings:

Figure 1 represents a top plan view.

Figure 2 is a side elevation.

Figure 3 is a side elevational view of one of the brush holders.

Figure 4 is a section on the line 4—4 of Figure 3.

Figure 5 is a perspective view of the scraper member.

Figure 6 is a perspective view of one of the posts.

Figure 7 is a plan view of the boot jack blank.

Figure 8 is a perspective view of the boot jack.

Referring to the drawings wherein like numerals designate like parts, it can be seen that the assembly consists of the pan 5 having the raised side walls 6—6, the end wall 7 and the shorter end wall 8. Between the side walls 6—6 and against the end wall 8 is disposed the brush 9, the bristles 10 of which are disposed upwardly toward the free ends of the brush holders 11—11. Each of these brush holders 11 consist of an elongated spring plate 12, the edge portions of which are provided with laterally disposed arm formations 13 each of which has an inwardly disposed cleat formation 14 for engaging the corresponding brush back 15 from which the bristles 16 extend. These bristles of the brushes 15 are disposed in opposed relation and the brush holders converge from their anchored ends toward their free ends to terminate over the aforementioned brush 9. As can be seen in Figure 6, the side walls 6—6 of the pan 5 are provided with

inwardly offset and oblique portions 17 defining indentations 18 for receiving the lower portions of the upstanding posts 19 each being provided with a foot portion 20 having a keyhole slot 21 therein.

The reduced end portions 22 extend against the inner sides of these offset portions 17 and are backed by the feet portions 23 of the scraper back 24 which extends across above the pan 5. Rivets 24a pass through each of the foot members 23, brush holder portions 22, oblique portions 17 and posts 18, to secure these parts together in the manner substantially shown in Figure 1.

Lips 26 extend inwardly from the side walls 6 to engage over and retain the brush 9 in place.

Obviously a person with soiled boots or shoes can scrape off mud and other foreign matter on the scraper bar 24 and subsequently brush the shoes by moving the same between the brushes 15. Dirt from these operations will fall into the pan 5 and when sufficient debris has collected in the pan the same can be dumped by disengaging the feet 20 from screws driven into a floor or other supporting surface.

Numeral 21 represents the boot jack which in blank form as shown in Figure 7 consists of a substantially V-shaped sheet of metal. This sheet is bent on the lines a—b to form the plate portion 28 having openings 29 therein through which rivets 30 are disposed for securing the jack to the end wall 7. The resulting portion 31 is bent laterally and adapted to rest on the surface 32. This foot portion 31 has the keyhole slot 33 formed therein for receiving the head 34 of a screw driven into the supporting structure 32.

The leg portions 35—35 are inclined upwardly as shown in Figure 2 and are bent or curved transversely with their channeled sides outwardly extending, the upper edge portions of the leg members 35 preferably overhanging the lower edge portions as suggested in Figure 8.

The legs 35—35 diverge in the manner shown in Figures 7 and 8 so that the heel portion of a boot can be engaged between the same for conveniently removing boots from the feet without employing the hands.

While the foregoing specifications sets forth the invention in specific terms, it is to be understood that numerous changes in the shape, size and materials may be resorted to without departing from the spirit and scope of the invention as claimed hereinafter.

Having described the invention, what is claimed as new is:

1. A cleaning apparatus of the character stated comprising a base having upstanding side walls, said upstanding side walls having indented portions, said indented portions of the walls being in opposed relation and having their back walls in angular converging relation with respect to each other, elongated spring members each having one end secured to a corresponding back wall of an indented portion of a side wall, a brush carried by each of the spring members, said brushes being carried by the opposed sides of the spring members and being set in converging relation by the converging disposition of the back walls of the indentations, and securing brackets, said brackets being provided with attaching portions disposed into the indented portions of the side walls, and common securing

means for securing the spring members and brackets to the back walls of the indented portions of the side walls.

2. A cleaning apparatus of the character described comprising a box-like base, inwardly converging formations at the inner side of the box-like base, elongated spring members each having one end secured to a corresponding converging formation, a brush carried by each of the spring members, said brushes being carried by the opposed sides of the spring members and being set in converging relation by the converging dispositions of the said formations, L-shaped securing brackets having one leg thereof disposed against the converging formations and common securing means for securing the spring members and brackets to the converging formations.

OLIVE H. COTTINGHAM.
